COMBINED BLANK HOLD-DOWN MEANS AND BURR-REMOVING MECHANISM FOR SCREW-SLOTTING MACHINES

Anthony Michael Putetti, Waterbury, Conn., assignor to The Waterbury Farrel Foundry & Machine Company, Waterbury, Conn., a corporation of Connecticut

Application December 15, 1953, Serial No. 398,296

4 Claims. (Cl. 10—6)

This invention relates to a screw-slotted machine, and more particularly to a burr-removing mechanism for such a machine.

As illustrated, the screw-slotted machine of the present application is of the type shown in the copending application of Joseph M. Schaeffer, Serial No. 280,767, filed April 5, 1952, now U. S. Patent No. 2,737,669 issued March 13, 1956, wherein a blank-carrying dial is rotatably mounted in a supporting head, which dial is provided with a plurality of radially disposed grooves in its outer face for reception of the screw blanks to be slotted. A saw or cutter is rotatably mounted within the carrier dial but upon an axis eccentric to that of the dial so that as the blanks are carried around by the dial, they will at one zone of their path be engaged by the slotted saw.

In the slotted operation burrs are often formed upon the blanks at the edge of the slot, which burrs require removal in some manner. It has been proposed to provide cutters integrally formed with the carrier dial and to rotate the blanks at one portion of their movement as they are carried around by the dial so as to engage the blank heads with the burr-removing cutters. In such an arrangement individual burr-removing cutters are provided at each of the blank-receiving slots of the dial, and it will be appreciated that when the cutters become dull, it is necessary to disassemble the device and remove the dial in order to sharpen the cutters or to replace the dial with another having sharp cutters thereon. In either case considerable effort and time is required for such an operation during which the slotted machine must stand idle.

It is usual in a slotted machine of this kind to provide some type of head ring or support secured to a stationary part of the machine to engage the heads of the blanks so as to retain them in the dial slots and prevent them from falling inwardly at the upper portions of their paths. According to the present invention, there is provided a ring removably secured to the dial which not only engages the heads of the blanks to retain them in the slots of the dial, but which is also provided with cutters to engage the side faces of the heads and remove the burrs therefrom. This head ring is, as stated, removable so that it may be readily removed from the carrier dial and either sharpened or replaced by a new one with little effort.

In addition, there is provided means for rotating the blanks at one portion of their paths, after they have been engaged by the slotted saw, so that the blank heads will be rotated in engagement with the cutting members on the head ring in order to remove the burrs therefrom.

Moreover, the removable head ring may be formed to support and retain and also cut the burrs from any type of screw head so that when it is desired to use the machine with a different type of screw, it is only necessary to apply the proper type of head ring constructed for that particular type of screw. Previously where the burr-

2

removing cutters were formed integrally with the carrier dial, it was necessary to use a different dial with each different type of screw head. Moreover, as all of the burr-removing cutters are provided on a single head ring, this ring can be removed and replaced conveniently, thus removing and replacing all the cutters as a unit, which is much more economical in regard to the time required for the operation than would be the removal and application of each of the cutters individually.

10 One object of the invention is to provide a new and improved burr-removing mechanism for a screw slotted or like device.

A still further object of the invention is to provide a screw-slotted machine having a carrier dial for the blanks and an internally eccentrically mounted screw-slotted saw with a head ring having cutters thereon registering with the slots in the dial to remove the burrs from the slotted heads after the slotted operation.

20 Still another object of the present invention is to provide a burr-removing device for screw-slotted machines of the character described wherein the burr-removing cutters are provided on a head ring removably secured to the carrier dial.

25 A still further object of the invention is to provide, in a screw-slotted machine of the character described, a head ring removably attached as a unit to the carrier dial, which head ring will not only engage the heads of the blanks to retain the latter in place in the dial, but will also be provided with cutters to remove the burrs from the blanks and to provide cooperating means for rotating the blanks at a certain position in their travel to effect engagement of the blank heads with the cutters.

30 To these and other ends the invention consists in the novel features and combinations of parts to be herein-after described and claimed.

In the accompanying drawings:

Fig. 1 is a front elevational view of a screw-slotted device embodying my invention;

Fig. 2 is a sectional view on line 2—2 of Fig. 1;

Fig. 3 is a sectional view through the blank-rotating mechanism on line 3—3 of Fig. 1;

Fig. 4 is a plan view looking in the direction of the arrows 4—4 on Fig. 3;

Fig. 5 is a sectional view through the carrier dial on line 5—5 of Fig. 1;

Fig. 6 is a front elevational view of the head ring having the burr-removing cutters mounted thereon;

Fig. 7 is a side elevational view of Fig. 6;

Fig. 8 and 9 are sectional views taken respectively on lines 8—8 and 9—9 of Fig. 6; and

Fig. 10 is a view similar to Fig. 9 but showing a section of a head ring for a screw having means at one side for cutting a burr from a round headed screw and means at the other side for cutting a burr from a screw having a head of another shape.

To illustrate a preferred embodiment of my invention I have shown in the drawings a screw-slotted device having a stationary head 10 in which is rotatably mounted a gear 11 having secured to the front face thereof a carrier dial 12. Rotatably mounted within the gear 11 is a shaft 13 which carries the slotted cutter 14. As shown more especially in Figs. 1 and 2, the axis of the shaft 13 is eccentric to that of the rotatable gear 11 so that the teeth of the cutting saw 14 will engage the heads of the blanks carried by the carrier dial 12 during one portion or zone of their movement.

The carrier dial 12 is provided upon its front face with a plurality of radially directed slots 15 to receive the screw blanks with the heads of these blanks projecting inwardly toward the axis of the dial. A feed-in wheel 16

(Fig. 1) is rotatably mounted forwardly of the carrier dial, this wheel being provided with a plurality of screw-receiving slots or notches 17 to receive screw blanks from any desired source such as a chute (not shown) and deliver these blanks to the slots 15 in the carrier dial.

A presser plate member 18 is provided forwardly of the dial, this member being of arcuate shape and extending over an arc of approximately 270 degrees (so as to clear the feed-in wheel 16), this carrier dial engaging the screw blanks at the side opposite the dial 12 so as to hold the blanks against the dial. This presser plate may be resiliently and adjustably held in place by screws 19 threaded into spring fingers of the plate 20 which is attached by screws 21 to a cover plate 22 which is in turn secured to the head 10.

The cover plate 22 is provided with an arcuate opening to receive the presser plate 18, and the position of the latter toward and from the face of the dial may be adjusted by the screws 19. Rotation of the presser plate with relation to the cover plate is prevented by the provision of a recess 23 formed in the presser plate 18 in which recess is received a lug or key 24 secured to the cover plate by a screw 25. Thus the presser plate is held in place but permitted movements toward and from the blank-carrying dial 12 as regulated by the screw 19 and the spring fingers of the plate 20.

At one portion of the presser plate 18 provision is made for rotating the blanks on their axes in order to bring their heads into engagement with the burr-removing cutters arranged on the dial, as will be hereinafter explained. For this purpose the presser plate is recessed, as shown at 27, Fig. 3, and slidably mounted in this recess is an insert 28 which may move toward and from the face of the dial. A spacer member 29 engages the rear face of the block 28, this member being engaged by an adjusting screw 30 threaded into a spring plate or finger 31 secured to the cover plate 22. It may be noted that the spring finger 31 is separate from the fingers of the plate 20 so that the pressure against the block 28 may be separately adjusted without affecting the adjustment of the presser plate 18.

Secured to the forward face of the member 28 is a member 32 having serrations 33 thereon adapted, as shown in Fig. 3, to engage the shank of a screw blank indicated at 34 and rotate this blank as it is carried past the serrated member by rotation of the dial 12. From the above, it will be seen that as the blanks are carried around by the dial, the pressure exerted upon them by the insert 28 may be separately adjusted by the screw 30, in order that the proper pressure may be exerted upon the blanks to rotate them when they arrive opposite the serrated member 32.

In order to retain the blanks from dropping out of the slots 15 in the face of the carrier ring and to provide burr-removing cutters to remove the burrs from the slotted blanks during their rotation by the serrated member 32, a head ring is secured to the carrier dial 12, this head ring being of the form shown in Figs. 6 and 7. This member is of circular form, as shown at 36, and is provided with axially directed grooves 37 cut across its peripheral surface to provide upstanding cutting teeth 38 having cutting edges 39 thereon. It will be understood that only one of the edges of the cutters 38 is a cutting edge as the blanks, upon rotation, will strike only one edge of these members. The cutting edges 39 are directed radially toward the center of the head ring 36, and the opposite edges of these members are substantially parallel to this edge.

This head ring 36 is secured within the carrier dial 12 by screws 40 (Fig. 2) so that the outer surfaces of the cutter members 38 stand against the inner periphery of the carrier and the cutting edges 39 face forwardly toward the screw blanks. As this member also serves as a retainer for the screws, each of the members 38 is slotted, as shown at 41 (Fig. 8), to receive an edge of

the head of the blank and permit the body portion of the ring to underlie a portion of the periphery of the head. As shown in Fig. 8, the blank 34 is a beveled headed screw and, therefore, the recess or notch 41 is similarly beveled so that it will engage the screw head over substantially the entire lateral surface as the screw is rotated, and thus the cutting edge 39 will cut the burr from the slot 42.

The head of the blank, as shown in Fig. 8, will rest against the inner wall 43 of the beveled slot 41 so as to restrain the blank from moving inwardly. Thus the head ring acts as a retaining ring secured to the carrier to hold the screws in place as well as providing a removable support for the cutters 38.

15 The head ring 36 is provided with openings 44 through which the screws 40 may be inserted to secure this member to the carrier ring, the openings 44 being made slightly larger than the body of the screws in order to permit adjustment of the head ring toward and from the face of the carrier dial as is desirable. This adjustment may be readily made by the provision of recesses 45 (Figs. 5 and 7) formed in the rear face of the retaining ring, these recesses having beveled front edges 46 against which impinges the pointed end 47 of adjusting screws 48 threaded into the carrier dial. Thus, by turning the screws 48 in the proper direction, the ring may be adjusted toward and from the face of the carrier dial in order to properly position the front faces of the cutting teeth 38 to engage the lateral faces of the heads of the blanks.

30 I prefer to so locate the head ring 36 with respect to the carrier dial that the cutting edges 39 of the teeth 38 are substantially at the center of the adjacent blank-receiving slot 15 so that the most efficient burring action will result as this edge will then be on the diameter of the head of the blank.

35 In Fig. 10 of the drawings I have shown a somewhat modified form of head ring in which the cutting teeth 32a are provided on one face with a beveled recess 41a and the cutters thus arranged to deburr a screw with a beveled head and on the other face with a recess 41b of arcuate shape to receive and cut the burr from a round headed screw. It will, of course, be understood that the shape of this recess should conform to the shape of the head of the screw with which it is used. By providing cutting edges on both faces of the cutting teeth 32a, one head ring may be provided with two cutting faces and, therefore, serve a double function. It will, of course, be understood that grooves of the same shape may be provided on each face of the teeth, and in that event it would only be necessary to turn the ring face for face when one edge becomes dull. In any event, a supporting surface 43 or 43a is shown in Fig. 10 which is provided for support of the head of the blank.

40 It will be apparent that I have provided a retaining ring on the carrier instead of on the presser plate as has been the case heretofore and that this head ring or retaining ring is removably attached to the carrier dial and is provided with a cutting tooth on each adjacent edge of the blank-carrying slots in the dial. When the teeth become dull, it is a relatively simple matter to remove the screws 40 and replace the head ring with another and to sharpen the edges of the one which has been removed. With the burr-removing cutters formed integrally on the head ring which is removably attached to the carrier, it is a simple matter to sharpen these cutters as compared to the work involved when the cutters are formed integrally with the carrier dial. Moreover, when the cutters are provided on a unitary member as the ring 36, they may be easily removed and replaced.

45 While I have shown and described a preferred embodiment of my invention, it will be understood that it is not to be limited to all of the details shown, but is capable of modification and variation within the spirit of the invention and within the scope of the claims.

What I claim is:

1. A screw-slitting machine comprising a head member, a carrier dial rotatably mounted therein having radially directed slots in a face thereof to receive the shanks of the screw blanks, means for slotting the heads of the blanks as they are carried in a circular path by the dial, pressure means for holding said blanks in said slots and comprising means adjacent one portion of said path following that portion in which the slotting is effected for rotating the blanks on their axes, said dial being of ring-like form and having an inner cylindrical periphery, a retaining ring, also having a continuous cylindrical periphery removably secured to the inner periphery of the dial and provided with means to engage the heads of the blanks and retain them in the dial, and said ring having a plurality of grooves cut across the peripheral surface thereof to provide cutting teeth adjacent the dial slots to remove the burrs from the blanks as they are rotated by said rotating means, said pressure means being disposed entirely outwardly of the cylindrical periphery of the retaining ring.

2. A screw-slitting machine comprising a head member, a carrier dial rotatably mounted therein having radially directed slots in a face thereof to receive the shanks of the screw blanks, means for slotting the heads of the blanks as they are carried in a circular path by the dial, pressure means for holding said blanks in said slots and comprising means adjacent one portion of said path following that portion in which the slotting is effected for rotating the blanks on their axes, said dial being of ring-like form and having an inner cylindrical periphery, a retaining ring, also having a continuous cylindrical periphery removably secured to the inner periphery of the dial and provided with means to engage the heads of the blanks and retain them in the dial, and said ring having a plurality of grooves cut across the peripheral surface thereof to provide cutting teeth adjacent the dial slots to remove the burrs from the blanks as they are rotated by said rotating means, said pressure means being disposed entirely outwardly of the cylindrical periphery of the re-

40 taining ring, and means for adjusting said ring axially of the dial.

3. A screw-slitting machine comprising a head member, a carrier dial of ring-like form rotatably mounted therein having radially directed slots in a face thereof to receive the shanks of the screw blanks, means for slotting the heads of the blanks as they are carried in a circular path by the dial, means adjacent one portion of said path following that portion in which the slotting is effected for

10 rotating the blanks on their axes, and a ring removably secured to the inner periphery of the dial having cutting teeth thereon adjacent the dial slots to cut the burrs from the blanks as they are rotated by said rotating means, said teeth having cutting edges at both faces of the ring whereby the ring may be reversed and the cutting edges at either side positioned adjacent the dial slots.

4. A screw-slitting machine comprising a head member, a carrier dial of ring-like form rotatably mounted therein having radially directed slots in a face thereof to receive the shanks of the screw blanks, means for slotting the heads of the blanks as they are carried in a circular path by the dial, means adjacent one portion of said path following that portion in which the slotting is effected for rotating the blanks on their axes, and a ring removably secured to the inner periphery of the dial having cutting teeth thereon adjacent the dial slots to cut the burrs from the blanks as they are rotated by said rotating means, said teeth being provided with cutting edges at both faces of the ring and having grooves in both faces thereof

20 25 30 to conform to the shape of the head of the blank being cut, and the groove upon one face being of a shape different from that of the groove upon the other face.
